UNITED STATES PATENT OFFICE.

MOSES ARTHUR KNAPP, OF OAKLAND, CALIFORNIA.

ROCK-DRILL.

1,138,612.

Specification of Letters Patent.

Patented May 4, 1915.

Application filed February 23, 1915 Serial No. 10,627.

To all whom it may concern:

Be it known that I, MOSES ARTHUR KNAPP, a citizen of the United States, residing at Oakland, in the county of Alameda and State of California, have invented a new and useful Improvement in Rock-Drills, of which the following is a specification.

My invention relates to the class of rock drills, and has for its object the provision of an affixed water tank on a rock drill, operable in all positions of the drill, to supply the water of a water air blast.

To this end my invention consists generally of a closed pressure piston to which is supplied water through the handle of the machine, and which closed piston or tank is supplied with low air pressure from the operating drilling engine, preferably from the exhaust of said engine; together with special 20 valved water connections from the tank to the hollow shank of the drill bit, air connection from the main air valve of the drill to the expansion space of the pressure cylinder fitting about the piston, means of controlling the amount of air blast, and other 25 valuable features, all of which are more particularly described in the accompanying drawings, in which —

Figure 1 represents a stoker rock drill 30 with front head and part of cylinder in section. Fig. 2 is a longitudinal section of the back head with a portion of the drill cylinder and pressure piston and pressure cylinder. Fig. 3 shows the corresponding 35 section of the rear end of the pressure piston and pressure cylinder. Fig. 4 shows in elevation the main feed valve of the drill. Fig. 5 represents the pinion operating the valve tube of the water tank. Fig. 6 shows 40 in section the valved end of the handle bar. Fig. 7 is an elevation of the spring valve ring about the leakage air exhaust of the front head. Fig. 8 shows the exhaust choking device.

Returning now to Fig. 1, number 1, is the drill bit having collar 2 and shank 3 inserted into front head 4. 5 and 6 are leakage air exhaust from the front head covered at will of the operator by the thin split- 50 ring spring 7. 8 is the axial water tube passing through the hammer 9, which hammer reciprocates in drill cylinder 10 by action of the operating valve in valve chest 11. 12 is the back head into which the pipe elbow 13 from air hose 14 feeds compressed air from the main air supply pipe 15. 16

is the handle of the main air feed valve, and 17 the handle of the pinion of the water tube valve. 20 is the hollow handle bar, 21 the exhaust choking device, and 22 the pressure 60 piston sliding in the pressure cylinder 23.

In Figs. 2 and 3, 30 is the tapped hole for air supply to the main air valve 32. This valve has main air supply passage 33 shown in dotted lines, which passage communicates 65 with main air passage 34, also shown in dotted lines as running into the metal of the drill cylinder to deliver air to the valve chest 11, Fig. 1. This section of the back head, and main valve 32 is taken at a level, 70 which cuts the second valve aperture 35, on the valve 32. This second aperture supplies air to the passage 36. This passage 36 communicates with a tapped hole 37 in the back head 12, into which is screwed a tube 38, 75 which extends back through the pressure piston 22, and tightly into open ended plug 39, in the closing piece 40 of the pressure piston. In the axial center line of the back head is drilled a hole 42 into the upper 80 tapped end of which is screwed the rear end of the water tube 8. Into this hole slips also the valve tube, or water tube valve 43, which is cut on one side in three places, making two rack gear teeth 44, which mesh with 85 the teeth of the pinion 45, shown in section. The other end of the tube valve 43 enters the hollow plug 46 in closing piece 40. A hole 47 in the tube 43 is shown as opening 90 into the piston 22, but would be closed were the tube moved downward farther into the plug 46 by rotation of the pinion 45. 48 is the exhaust port to the atmosphere for the air of tube 38, and 49 is the passage to port 48 from valve 32. From the hollow 95 of the drill cylinder 10 opens an exhaust port 51, exhausting through passage 52 to the exhaust outlet 53. The passage 52 communicates with a passage 54 in the back head, which enters a hole 55, tapped in the back 100 head. In this hole 55, screws a tube 56, open at its lower end into the bottom of the interior of the pressure piston 22. In the upper enlarged end of passage 54, a small check valve 57 moved by spring 58, closes 105 the end of passage 52. In the lower end of tube 56, extends a grooved pin 59, about which is a check valve 60, moved by spring 61. From interior of pressure piston 22 110 opens water passage 65 to the tapped boss 66, into which screws the handle bar 20. In the bottom of this tapped boss lies a flap

check valve 67 overlaid by a ring 68, and this by a circular wire screen 69. About tapped boss 66, screws ring 70 holding in place loosely the exhaust choking ring 71, and its circular spring 72. On the ring 71 is pin 73, and on the back head is pin 74, which two pins hold the ends of the springs 72, as shown more clearly in Fig. 8. About the top of pressure cylinder 23 screws the gland 75, holding the packing 76. The lower end of the cylinder 23 is closed by pointed plug 77.

In Fig. 4, the main air feed valve 32 is shown in elevation in a section of a portion of the back head 12, as having the two air passages 33 and 35; both communicating with the air inlet passage 30. The air passage 35 extends around nearly half the circumference of the valve, as shown in Fig. 2. Since the two open ends of passage 33 on either side of the valve are comparatively narrow, the main air feed to the operating valve can thus be shut off without closing the feed of air to the pressure cylinder 23. The pressure piston can then be exhausted into exhaust port 48, by still further turning off the valve in the same direction, opposite to the movement of the hands of a watch.

In Fig. 5 is shown a double taper pin 79, fitting into a section of a portion of the back head. It has an upper large tapered portion 80, and a lower tapered portion 81, fitting simultaneously in their tapered holes in the metal of the back head. At the center of the pin is the pinion 45, shown as engaging in the notch of the tube 43. Pin 79, and valve 32, and their handles 16 and 17, are held in place by the ordinary nuts and washers, used on such valves, but not shown here.

In Fig. 6, in the hollow bent end 83 of the handle bar 20, is a diaphragm 84, through which plays a pin 85, on which screws a head 86 over a spring 87, compressed against the diaphragm. On the other end of the pin 85, is riveted a hooped half cylindrical piece 89, which, when pushed out, as shown in the drawing, turns freely with the pin, and acts as a cup or trough to guide a falling stream of water into the hollow handle bar. The circular top 90 of the piece 86 makes a tight fit in the handle bar when allowed to close by the extension of spring 87.

In Fig. 7, the split ring number 7, Fig. 1, is shown as having two symmetrically opposite beveled edges 91 and 92, adapted to close not too tightly, the openings of passages 5 and 6, Fig. 1, when the ring is turned about the drill axis; thus regulating the escape of the leakage air past the hammer and forward into the front head. In consequence, this ring 7, regulates also the flow of such air into the drill shank.

In Fig. 8, is shown a bottom or inside view of the ring 71, Fig. 2, as a section taken on line A. A. Fig. 2, looking from left to right.

I show also in dotted line the position of the outlet 53, and of the circular spring 72 at rest. As seen here, if the flaring wing 93 of the ring 71 is moved out opposite the circle of outlet 53, the end of the spring 72 is caught by pin 73 of the ring, and since pin 74 is fixed to the back head, this motion bends spring 72, which when freed, moves the wing 93 from in front of outlet 53.

In the operation of my invention, the drill being extended by the passage of air through port 35, passage 36, tube 38 and plug 39 to the space between closing piece 40, and pointed plug 77; the pin of the handle bar 20 is pushed in by the finger of the workman 80 and water from a can or dipper is poured into hood 89, turned in position to catch such water stream. The water passes screen 69, and valve 67, to the interior of piston 22. Being held upright by the pressure piston 85 with water against piece 40, the drill is started operating, and the exhaust air blows past the two check valves, 57 and 60, into the water tank. A moment's pressure on the wing 93 of ring 71, chokes the exhaust to 99 such an extent, that this pressure in the tank is quite sufficient, or if the air is taken from other points, the pressure may be sufficient, without choking the exhaust. The handle 17 is now turned, so that the pinion 45, moves 95 the tube 43 into position as shown, so that hole 47 opens into the bottom of the tank. This position of tube 43 closes the opening of the lower of the notches cut in tube 43 for the pinion 45. Water now flows out of hole 100 47, tube 43, and tube 8 to the hollow of shank 3 of the drill bit. The holes 5 and 6 being largely closed by the ring 7, the air leaking past the front of hammer 9, blows out of the hollow drill rod with the water supplied 105 as explained.

On stopping the drill, the air in the tank may be allowed to exhaust by a downward movement of tube 43 by a turning of pinion 45, so that the lowest of the notches for the 110 pinion teeth opens into the tank piston at the top, exhausting the air, and allowing more water to be poured into the tank. If the drill is mounted on a column, so that the water flows forward in the tank in piston 115 22, then the tube 43 is moved backward to allow water to flow, and moved forward to exhaust the air pressure.

Except where so specified, I do not confine my claims to the particular construction shown in these drawings.

The air supply to the interior of piston 22 may be from any convenient source, and other than from the exhaust of the drill, as for example, or it may be from a special exhaust port, or from some other point of supply of compressed air, or expanded and exhausting air in the drill. I show a means of supplying to the piston a low pressure air supply suitable to the conditions of the 125 130

problem. Also there may be other, and more direct means used for controlling the supply of air to the drill shank than that I show. Similarly any other means may be 5 used for choking the exhaust momentarily at will of the workman to produce a higher pressure in the tank piston 22. Also the water tank may be otherwise affixed to the drill than as I have shown, and on other 10 forms of drilling machines besides the stoper drill.

The tube 56 is not a mechanical necessity in my invention, but only a precaution against the backward leakage of water into 15 the drill cylinder when the stoper drill is thrown to one side at quitting time. The tube may be dispensed with, and the second valve 60 be placed in the back head.

I have shown the water tank as formed of 20 the pressure piston of a stoper drill having "reverse feed" as explained. This pressure piston is a cylinder attached to the back head, and extending axially to the rear from the back head. I may use such cylindrical 25 tank fitting inside the piston of a stoper drill with direct feed if desired, and leaving out tube 38 may retain the other features of the above described invention. Where I use 30 in this design two separated valves for discharging the water from the tank to the water passage; these two valves may be combined if desired into one three-way valve with appropriate connections.

Having thus described my invention, what 35 I claim as new and desire to protect by Letters Patent, is,

1. In a rock drilling apparatus having a drilling engine and a hollow drill bit; a water tank affixed to said drilling engine and, a 40 connection from said water tank to said hollow bit.

2. In a rock drilling apparatus having a drilling engine and a hollow drill bit; a water tank affixed to said drilling engine, connection 45 from said water tank to said hollow bit, and means for supplying an air pressure to said water tank.

3. In a rock drilling apparatus having a drilling engine and a hollow drill bit; a water tank affixed to said drilling engine, connection 50 from said water tank to said hollow bit, and means of supplying an air blast to said hollow bit in such a manner that said air and said water shall be delivered at the 55 cutting end of said drill bit as a combined blast of air and water.

4. In a rock drilling apparatus having a drilling engine and a hollow drill bit; a water tank affixed to said drilling engine, connection 60 from said water tank to said hollow bit, means of supplying an air blast to said hollow bit and means of controlling the amount of flow of water from said water tank to said hollow bit.

65 5. In a rock drilling apparatus having a

drilling engine and a hollow drill bit; a water tank affixed to said drilling engine, connection from said water tank to said hollow bit, means of supplying an air blast to said hollow bit in such a manner that said air 70 and said water shall be delivered at the cutting end of said drill bit as a combined blast of air and water and means of controlling the amount of said air blast.

6. In a rock drilling apparatus having a 75 drilling engine and a hollow drill bit; a water tank affixed to said drilling engine, connection from said water tank to said hollow bit, means of supplying an air blast to said hollow bit, means of controlling the amount 80 of flow of water from said water tank to said hollow bit and means of controlling the amount of said air blast.

7. In a rock drilling apparatus having a 85 drilling engine and a hollow drill bit; a water tank affixed to said drilling engine, connection from said water tank to said hollow bit, and means for supplying an air pressure to said water tank, said means consisting of a connection from a source of compressed 90 air in said drilling engine to said water tank.

8. In a rock drilling apparatus having a 95 drilling engine and a hollow drill bit; a water tank affixed to said drilling engine, connection from said water tank to said hollow bit, and means for supplying an air pressure to said water tank, said means consisting of a connection from the exhaust air 100 passage of said drilling engine to said water tank.

9. In a rock drilling apparatus having a 105 drilling engine and a hollow drill bit; a water tank affixed to said drilling engine, connection from said water tank to said hollow bit, means for supplying an air pressure to said water tank, said means consisting of a connection from a source of compressed air 110 in said drilling engine to said water tank, and a check valve on said last named connection.

10. In a rock drilling apparatus having a 115 drilling engine and a hollow drill bit; a water tank affixed to said drilling engine, connection from said water tank to said hollow bit, means for supplying an air pressure to said water tank, said means consisting of a connection from the exhaust air passage of 120 said drilling engine to said water tank, and means for partially closing the said exhaust.

11. In a rock drilling apparatus having a 125 drilling engine and a hollow drill bit; a water tank affixed to said drilling engine, connection from said water tank to said hollow bit, and a plurality of openings from said tank to said connection.

12. In a rock drilling apparatus having a 130 drilling engine and a hollow drill bit; a water tank affixed to said drilling engine, connection from said water tank to said hollow

- bit, a plurality of openings from said tank to said connection, and a cut off valve operative upon each of said openings to cut off, or permit the passage of air or water through said opening to said hollow bit.
13. In a rock drilling apparatus having a drilling engine and a hollow drill bit; a water tank affixed to said drilling engine, connection from said water tank to said hollow bit, two openings from said tank into said connection, a cut off valve operative upon each of said openings and a connection between said two valves, whereby either one is closed when the other is opened.
14. In a rock drilling apparatus having a drilling engine, a drill bit and a handle bar adapted to give an oscillatory rotating motion to said drill bit; a water tank affixed to said drilling engine adapted to feed water to allay the dust of drilling, a water entrance port governing the feed of water to said tank, said port being upon said handle bar and connected to said tank by a passage through said handle bar.
15. In a rock drilling mechanism of the stoper type, having a hammer, a drill bit, and a pressure apparatus axially in line with said hammer and drill bit; a water tank affixed to said drilling mechanism and inclosed in said pressure apparatus, and means whereby the water of said tank is fed to the forward part of said drilling mechanism for the purpose of allaying the dust of drilling.
16. In a rock drilling mechanism of the stoper type, having a pressure apparatus consisting of a pressure piston attached to the drilling mechanism and a pressure cylinder sliding about such pressure piston; a water tank inclosed in said pressure piston and an air passage from said drilling mechanism to the inclosed space of said pressure cylinder, consisting of a tube passing from said drilling mechanism throughout the length of said pressure piston.
17. In a rock drilling apparatus having a drilling engine, a drill bit and an inclosed passage from said drilling engine along said drill bit to near its cutting end; a water tank affixed to said drilling engine and a connection from said water tank to said inclosed passage.
18. In a rock drilling apparatus having a drilling engine and a hollow drill bit; a water tank affixed to said drilling apparatus, and means whereby the water from said tank is delivered into the hollow of said hollow bit.
19. In a rock drilling apparatus having a drilling engine and a hollow drill bit; a water tank affixed to said drilling apparatus, means whereby the water from said tank is delivered into said hollow of said bit, said means consisting in part of an air pressure in said tank and of a tube delivering a stream of water into said hollow of said bit.
20. In a rock drilling apparatus having a drilling engine, a drill bit and an inclosed passage from said drilling engine along said drill bit to near its cutting end; a water tank affixed to said drilling apparatus and means whereby water flowing from said tank is delivered into said inclosed passage.
